UNITED STATES PATENT OFFICE.

GUY L. KENNEDY, OF SAN FRANCISCO, CALIFORNIA, ASSIGNOR TO NATIONAL CARBONATED LIQUID CO., OF SAN FRANCISCO, CALIFORNIA, A CORPORATION OF CALIFORNIA.

CARBONATING APPARATUS.

996,589.

Specification of Letters Patent. Patented June 27, 1911.

Application filed September 2, 1909. Serial No. 515,981.

To all whom it may concern:

Be it known that I, GUY L. KENNEDY, a citizen of the United States, residing at San Francisco, in the county of San Francisco and State of California, have invented new and useful Improvements in Carbonating Apparatus, of which the following is a specification.

The present invention relates to an apparatus by which a mixture of compressed gas and liquid may be thoroughly agitated so as to aerate or carbonate the liquid in the most perfect manner possible while an advanced portion of the same stream of liquid is being dispensed, and in which, at the same time, the aerated liquid can be cooled, so as to render it palatable when so dispensed.

In the accompanying drawing the figure is a vertical section of my improved agitating and cooling apparatus, certain parts being shown in side elevation.

Referring to the drawing, 1 indicates a pipe, into which, by suitable means, commingled gas and liquid at high pressure are charged, and through which said commingled fluids flow.

The pipe 1 is connected with one end of a helical coil of pipe 2 in a receptacle 3, the other end of said pipe 2 being connected by a flexible pipe 4 with a dispensing siphon 5. Said receptacle 3 is kept filled with ice or other cooling medium, by which the contents of said coil are cooled. Within said coil, and also within the pipes 1 and 4 connected to the coil, are contained a series of concave circular riffles 6 which are centrally strung or threaded at suitable intervals on a wire 7. Said riffles are so arranged that they present their concave surface to the liquid as it flows therethrough, and they are made of slightly less diameter than the internal diameter of the pipe containing them, so that the com-

mingled gas and liquid, flowing within the pipe, repeatedly impinge against the concave surface of a riffle and are deflected and compelled to pass around a riffle edge and are thus repeatedly agitated.

In prior devices, the gas and liquid are agitated violently, but only once, generally by means of a rotary agitator in a reservoir or tank, whereas in my improved means the gas and liquid are subjected to a large number of successive agitations, caused solely by the pressure and flow of the gas and liquid, permitting the liquid to absorb the gas to a certain extent before each subsequent agitation takes place.

I claim:

1. A device of the character described, comprising a pipe adapted to be connected at one end with a source of supply of gas and liquid under pressure, and at the other end with a dispensing device for dispensing aerated liquid, and means for agitating gas and liquid passing through said pipe, comprising a series of concave riffles arranged with their concave surface directed toward the first named end of said pipe, and a wire centrally connecting said riffles, substantially as described.

2. A device of the character described, comprising a receptacle, a coil of pipe therein, and means for agitating fluids passing through said pipe comprising a series of riffles within said coil, spaced at suitable intervals, and a wire connecting said riffles, substantially as described.

In testimony whereof I have hereunto set my hand in the presence of two subscribing witnesses.

GUY L. KENNEDY.
